Des. 242,212

Patented Nov. 9, 1976

242,212

CLEANING HEAD

Carl Parise, 3685 Downey Ave., Reno, Nev. 89503, and
James M. Wimsatt, 155 Pintail Drive, Carson City,
Nev. 89701

Filed Jan. 20, 1976, Ser. No. 650,637

Term of patent 14 years

Int. Cl. D7—05

U.S. Cl. D15—63

FIG.1

FIG.2

FIG.3

FIG. 4

FIG. 5

FIG. 1 is a side elevational view of a cleaning head, showing our new design;

FIG. 2 is a front elevational view of a cleaning head, showing our new design;

FIG. 3 is a top plan view thereof;

FIG. 4 is a rear elevational view thereof; and

FIG. 5 is a bottom plan view thereof.

The side of the cleaning head which is not shown is a mirror image of the side disclosed in FIG. 1.

We claim:

The ornamental design for a cleaning head, as shown and described.
